UNITED STATES PATENT OFFICE

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS

CAR DOOR

Application filed January 24, 1929. Serial No. 334,614.

This invention relates to improvements in car doors.

An object of the invention is to provide a strong and light metallic car door which will be braced in all directions, and wherein the use of countersunk rivets is avoided wherever possible.

Another object of the invention is to provide a door having a body portion made up of three metallic panels having marginal reinforcements along the top, bottom and side edges, and provided with diagonal braces adjacent the four corners, in conjunction with a continuous embossment in the central panel affording both horizontal and vertical strength, and wherein the embossment is arranged to distribute or continue the strengthening properties of the marginal edge formations and diagonal braces throughout the length and breadth of the door.

Another object of the invention is to provide for outward embossments of the paneling at the lower margin of the door for the purpose of providing additional space within which the door rollers may be contained.

A still further object of the invention is the bracing of the corners of the door by brackets each having a body section in the inner plane of the door and angularly related flanges connecting the horizontal and vertical walls of the framework of the door.

It is also an object of the invention to provide brackets at the inner side of the door to brace the marginal structure relative to the paneling to thereby prevent distortion of the sealing panel when the door abuts the door stops.

Other and further objects of the invention will more clearly appear from the description and claims hereinafter following.

In the drawings forming a part of this specification, Fig. 1 is a side elevational view of that portion of a box car illustrating the door and part of the framing identified with the car construction. Fig. 2 is a vertical sectional elevational view through the door taken on a line corresponding substantially to a line 2—2 of Fig. 1. Fig. 3 is a broken horizontal sectional view on an enlarged scale, taken on a line corresponding substantially to

the line 3—3 of Fig. 1. Fig. 4 is an enlarged detail sectional view taken through the door and car construction, said view being taken on the line 4—4 of Fig. 1, said view being broken intermediate the top and bottom margins of the door. Fig. 5 is a perspective view partially in section of an enlarged corner portion of the door taken on a line corresponding substantially to the line 5—5 of Fig. 4, this view showing in dotted lines the outer flanges of the door frame. Fig. 6 is a horizontal sectional detail view on a line corresponding substantially to a line 6—6 of Fig. 1, the view showing the door in its fully opened position and abutting the door stops on the car framing. Fig. 7 illustrates a somewhat different embodiment of the construction at the bottom of the door, in which the outwardly extended pan-shaped embossment is disposed only at each of the door support brackets, instead of extending the full length of the door as illustrated in Figs. 1 and 4.

As shown in the drawings, the car is provided with a door opening closed by the improved door construction which may be generally indicated by the reference character A. At the upper portion of the door opening there is provided a Z-bar 10 having one flange 11 secured to the car side wall, with the web projecting outwardly of the door opening and provided with a depending flange 12. To the flange 12 is secured a smaller Z-bar 13, arranged in such manner as to provide space between the free flange 12 thereof and the adjacent portion of the flange 12 of the Z-bar 10, providing a guide for the upper end of the door, as best shown in Fig. 4. The front and rear door posts preferably are in the form of angular members 14 and 15, best shown in Fig. 3, each of the angle members having one flange secured to the adjacent portions of the car wall by bolts indicated at 16, while the other flange projects outwardly substantially at right angles to the wall of the car. The bottom of the door opening is defined by the floor 17 of the car covered by a threshold plate 18. The outer margin of the floor 17 bears against a block 19 which is secured to

the side sill 20 of the car by bolts indicated at 21. Secured to the side sill 20 are a plurality of track-supporting brackets 22, said brackets being fixed to the car structure by bolts 23 extending through the block 19, floor 17 and threshold plate 18, the brackets also being supported by the bolts 21. Each of the brackets 22 at its outer end is cut out as indicated at 24 to provide a guide, and outwardly of the cut-out portion an angular member 25 is secured to each bracket 22 to provide a track for rollers carried by the door as hereinafter referred to.

The door proper, indicated generally by 15 the reference letter A, comprises a framework including a top Z-bar 26, a Z-bar 27 for the forward edge, and a modified Z-bar construction 28 at the rear edge, the bottom of the frame comprising a fabricated structure hereinafter referred to more in detail. Each of the Z-bars has one flange disposed in the inner plane of the door as indicated at 29, and the web 30 extending outwardly substantially at right angles to the inner plane 20 of the door, with the remaining flange 31 disposed inwardly in line with, or defining the outer plane of the door frame. The flange 29 of the Z-bar 27 is adapted for reception within a grooved member 32 attached to the door post 14. The flange 29 of the Z-bar 28 is curved as indicated at 33 to form a sealing member which co-operates with the angular part 34 secured to the door post 15.

35 The covering for the door frame comprises an upper sheet metal panel 35, a lower sheet metal panel 36 and a central sheet metal panel 37, all of the panels having adjacent overlapping edges secured together 40 by rivets indicated at 380. The top and side edges of the upper panel 35 are secured by rivets to the outer flanges 31 of the Z-bars. The adjacent edges of the central panel 37 are also secured to the flanges 31 of the Z-bars 27 and 28 by rivets. The side edges of the lower panel 36 are likewise secured to the flanges 31 of the Z-bars 27 and 28.

At the inner side of the door and lying within the space defined by the webs 30 of 50 the Z-bars 26, 27 and 28 are upper diagonally disposed bracing members 38 and lower oppositely arranged diagonally disposed braces 39. Each of the braces has a rearwardly extending embossment 390 and edge 55 flanges 40, the embossment terminating short of the ends of the member to provide flat portions at opposite ends, one of the flat portions being secured to the inner side of the flange 31 of the Z-bar 27 by rivets 41, and the opposite flattened end portion being secured by rivets 42 to the flange 31 of the top Z-bar 26, while the flanges 40 are secured to the body portion of the panel 35 by rivets 43, the brace extending diagonally 60 from the Z-bar 26 across the juncture of the

panels 35 and 37 and being secured to the flange 31 of the Z-bar 30 as best shown in Figs. 1 and 2. The diagonal brace at the opposite upper corner of the door is of the same character except for its opposite disposition. The braces 39 at the bottom of the door are arranged in the same manner as those at the upper end of the door, extending from the Z-bars 27 and 28 across the joint between the central panel 37 and bottom panel 36, and being secured to the outer flanges 31 of the Z-bars 27 and 28 at one set of ends and being secured at their opposite set of ends to a fabricated bottom construction hereinafter described in detail, 75 both the panels 36 and 37 being secured to the diagonal braces. Both of the panels 35 and 36 are provided with a plurality of horizontally extending corrugations, 44 and 45, the corrugations 44 of the panel 35 crossing 80 or intersecting the planes defined by the braces 38, while the corrugations 45 intersect or extend across the planes defined by the diagonal members 39.

The central panel 37 is provided with an embossment having vertical portions 46—46 formed adjacent the side edges of the panel, the vertical portions merging into upper and lower horizontal portions 47 so as to form a rectangular continuous corrugation or embossment with rounded corners. As best shown in Figure 3, the embossment is so formed that the outermost portion or crest of the embossment indicated at 48 extends or protrudes outside of the plane of the flanges 31—31 of the frame, while the central or dished portion 49 extends approximately midway between the planes defined by the inner flanges 29 of the Z-bars and the outer flanges 31 of the Z-bars, thereby disposing 105 the bottom of the embossment in line with the planes defined by the diagonal members 38 and 39, it being apparent that the embossed formation, in conjunction with the remaining elements of the door, results in extending or continuing the strength-giving qualities of the upper and lower diagonal members from one end of the door to the other and from one side of the door to the opposite side thereof.

110 The lower edge of the door is of peculiar formation and arranged to provide a tubular formation for strengthening the door and providing means for carrying the rollers. In providing the tubular formation, the lower edge of the panel 36 is provided with an outwardly extending horizontally disposed embossment 50 which preferably terminates short of the lower edges of the adjacent flanges 31 of the Z-bars 27 and 28, as indicated at 51. At the lower extremity of the embossment 50, there is provided an inwardly extending, horizontally disposed web 52 having an opening 53 through which a roller 115 is adapted to project, the inner extremity of 120

the web 52 terminating in a depending vertically arranged flange 54 which is offset to lie outwardly of the plane defined by the flanges 29 of the Z-bars 27 and 28. A facing plate is provided which has a vertical flange 55 disposed against the inner side of the outer wall of the embossment 50, said facing plate having a horizontally extending web 56 disposed above the web 52, the web 56 extending inwardly and merging into a vertically arranged portion 57 lying substantially within the plane defined by the flanges 29 of the Z-bars, the vertical portion 57 having an offset 58 extending toward the outer plane of the door and terminating in a vertically extending flange 59 which abuts against the flange 54 and is secured thereto by full-headed rivets 60, it being pointed out that by reason of the offset construction beneath the tubular formation, there is no necessity for counter-sinking the securing rivets.

There are, of course, at least two rollers associated with the door, but since they are the same in construction, only one will be described in detail. The roller construction includes a plate 61, the upper portion of which is riveted to the outer wall of the embossment 50, being extended downwardly and provided with a bearing 62, and a guide portion 630, the latter being adapted to co-operate with the track 25 to prevent too great inward movement of the door. Disposed in the bearing portion 62 is an axle 63 upon which the roller proper 64 is mounted, the inner end of the axle being supported in a plate 640 secured to the flanges 54 and 59, the roller projecting through the opening 53 into the tubular formation. The plate 640 is provided with an extension 65 forming an inner guide adapted to co-operate with the track to prevent outward movement of the door.

The door is further reinforced by brackets best shown in Figure 5, each corner of the door being provided with one of the brackets, the upper brackets being indicated by the reference character 66 and the lower brackets by the reference character 670. Each of the brackets comprises a flange 67 secured to the web 30 of the Z-bar 26 and an angularly extending flange 68, in Fig. 5, secured to the web 30 of the Z-bar 28, by rivets indicated at 69. At the inner or rear edges of the flange portions 67 and 68, there is formed a plate-like member 70 which integrally connects the flanges 67 and 68, the plate 70 and the flanges 67 and 68 being so proportioned that the plate 70 lies in the inner plane of the door or substantially coincident with the inner flanges 29 of the Z-bars 26, 27 and 28. The brackets 670 at the bottom of the door are, of course, reversed in position, the flange 67 of each one being secured to the horizontally extending web 56 of the face plate, each of the latter brackets providing a plate sim-

ilar to 70 disposed in the inner plane of the door.

The rear edge of the door is also reinforced to obviate distortion when the door is moved against stops. As best shown in Figures 1 and 6, stops 71-71 are provided on the car adapted to co-operate with the rear edge of the door. The door in line with each of the stops 71-71 is provided with a reinforcing bracket 72 having a flange bearing against the web 30 of the Z-bar 28, and being provided with a flange 73 secured to the panel, in this way preventing distortion at the edge of the door which might occur due to the heavy impacts which must be sustained thereby.

In Fig. 7, there is shown a slightly different form of the bottom construction of the door and the manner in which the rollers are associated therewith. In this form of the invention, the corrugation or embossment 50, instead of extending entirely between the rollers as shown in Fig. 1, is localized or restricted to a portion of the door immediately in the vicinity of the roller, the embossment being indicated at 730. Since the other parts of the roller construction are identical with those heretofore described, the same reference characters will be utilized in designating like parts.

By the above described arrangement, it will be appreciated that the strength-giving qualities of the diagonal members at the top and bottom of the door, in conjunction with the corrugations in the upper and lower panels, are extended and made continuous through the provision of the corrugated central panel wherein the plate-like portion of the panel is arranged within the plane of the diagonal members, while the vertical and horizontal portions of the embossment in the central panel co-act with the adjacent portions of the diagonal members to likewise continue and enhance the re-inforcement of the door vertically and horizontally, as well as in diagonal directions. The bottom construction of the door provides a tubular formation of great strength which co-operates with an offset roller construction permitting the use of full-headed rivets and avoiding the necessity for counter-sinking rivets at points where the weakness due to this factor has heretofore caused considerable difficulty. The formation and disposition of the corner brackets is such that a plate-like member of substantial depth is presented edge-wise to the stresses imposed thereon and affords its strength-giving qualities in the inner plane of the door, thereby obviating weaknesses which have hitherto existed in this portion of the door.

While I have herein shown and described what I now consider the preferred manner of carrying out my invention, the same is merely illustrative and I contemplate all

changes and modifications that come within the scope of the claims appended hereto.

I claim:—

1. In a car door having a framework of appreciable depth, said door having paneling disposed in the outer plane of the framework, said paneling having a lower marginal portion inwardly directed to present an inwardly extending horizontal web and downwardly extending flange spaced from the inner plane of the door; and a facing plate disposed in alignment with the inner face of the door and secured to the paneling above the horizontal web to provide with the paneling and web a tubular formation, said plate being offset outwardly and downwardly below the tubular formation and secured to the downwardly depending flange of the paneling, said secured portions being disposed beneath the major depth of the door and protected by the overhanging portions thereof.

2. In a sliding car door, the combination with vertical marginal members of appreciable depth, said members having inwardly extending flanges; of metal paneling secured to said flanges, said paneling at the lower margin of the door being deflected inwardly to provide a horizontally extending wall and downwardly to provide a depending flange, said depending flange being spaced intermediate the inner and outer planes of the vertical marginal members; and a facing plate secured to the inner face of the door above the horizontal wall and having a portion disposed downwardly substantially in alignment with the inner plane of the marginal members, said plate being outwardly offset at its lower margin toward, and joined by rivets to, the depending flange of the paneling, the joint thus formed being disposed beneath the major depth of the door and within the inner and outer planes of the marginal members.

3. In a sliding car door having a marginal framework of appreciable depth, said door having paneling disposed in the outer plane of the framework, said paneling being deflected inwardly and thence downwardly to present a depending flange, and a face plate disposed at the inner plane of the door adjacent the lower margin thereof, said facing plate adjacent its upper portion being deflected inwardly and upwardly and united by said last named portion with the paneling, said facing plate at the lower margin of the door being deflected outwardly and downwardly to present a depending flange adapted to overlie the depending flange of the paneling, and roller supporting means having portions overlying the outer face of the paneling and the outer surface of the depending flange, said respective faces of the paneling and the face plate being united with the roller supporting means by rivets having the heads thereof disposed below and

entirely within the depth of said door, whereby said rivet heads on the inner face of the door clear the inner face of the facing plate.

4. In a sliding car door the combination with a marginal framework of appreciable depth; of paneling disposed substantially in the outer plane of the door, a facing plate disposed substantially in the inner plane of the door; said facing plate and body paneling being deflected inwardly towards each other and formed with depending flanges adapted to be riveted together, said depending flanges and the rivet heads being disposed within the plane of the door; and door carrying brackets secured to the outer face of the paneling and to the depending flange thereof, said paneling adjacent the bracket having an outwardly extending pan-shaped embossment outstanding from the main plane of the door and door rollers carried by said brackets, said rollers being extended within the embossment.

5. In a car door, the combination with a framework of appreciable depth including upper horizontal and side vertical marginal members, said members having flanges in the outer plane of the framework; of metallic paneling overlying the said flanges of the marginal members and secured thereto, said paneling at its lower end being bent inwardly to present a horizontal flange and thence downwardly to present a depending flange, said paneling at its lower end being rigidified by a pan-shaped embossment formed in the plate and extending outwardly beyond the outer plane of the framework; and a face plate substantially in the inner plane of the framework, said face plate being provided with upper and lower offsets respectively connected with the inner face of the panel and the depending flange, said face plate member and the pan-shaped embossment cooperating to provide a tubular formation at the lower margin of the door of greater depth than the depth of the framework.

6. In a car door formed of appreciable depth, a door having a lower margin in the form of a Z shape with a wall horizontal and a depending flange; a bracket overlying said door and secured to the depending flange and to the main body section of the panel; a roller carried by said bracket and having a portion thereof extended through the horizontal wall of the Z-shaped portion, said door being provided at the roller with a bulged out portion to present a door of increased depth for the purpose of accommodating the roller therein.

7. A metallic car door of appreciable depth and having an offset lower edge construction comprising a plurality of plies of sheet metal shaped to provide a tubular formation with depending flanges, the outer defining wall of

said tubular formation being offset outwardly beyond the main plane of the door and the depending flanges being offset outwardly of the inner plane of the door.

- 5 8. A metallic car door of appreciable depth and having an offset lower edge construction comprising a plurality of plies of sheet metal shaped to provide a tubular formation with depending flanges, the outer defining wall of
- 10 said tubular formation being offset outwardly beyond the main plane of the door and the depending flanges being offset outwardly of the inner plane of the door; and roller-supporting means having portions overlying the
- 15 outer wall of the tubular formation and the outer surface of the depending flanges and secured to said wall and flanges, said roller extending into said tubular formation.

In witness that I claim the foregoing I have
20 hereunto subscribed my name this 21st day of
January, 1929.
